(57) **CLAIM**

The ornamental design for a hanging plate of ceiling fan, as shown and described.

DESCRIPTION

FIG. 1 is a perspective view of a hanging plate of ceiling fan showing my new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof.

The evenly-spaced broken lines illustrate portions of the hanging plate of ceiling fan that form no part of the claimed design.
